UNITED STATES PATENT OFFICE.

JOHN M. THOMSON, OF SOURLAKE, TEXAS.

SECTIONAL LINK.

1,283,972.

Specification of Letters Patent.

Patented Nov. 5, 1918.

Application filed July 6, 1918. Serial No. 243,591.

To all whom it may concern:

Be it known that I, JOHN M. THOMSON, a citizen of the United States, and a resident of Sourlake, in the county of Hardin and State of Texas, have invented a new and Improved Sectional Link, of which the following is a full, clear, and exact description.

The object of the invention is to provide a new and improved sectional link adapted to be readily opened for engagement with the parts to be connected with each other and then adapted to be closed and locked to hold the parts in coupled relation. Another object is to provide a sectional link more especially designed for use on oil well drilling tools having clevises and bails fixed on the blocks or tools. Another object is to prevent bending of the link and throwing it out of alignment with the connected parts when subjected to a heavy pull or strain.

With these and other objects in view, the invention consists of certain novel features of construction as hereinafter shown and described and then specifically pointed out in the claims.

A practical embodiment of the invention is represented in the accompanying drawings forming a part of this specification, in which similar characters of reference indicate corresponding parts in all the views.

Figure 1 is a side elevation of the sectional link with one of the locking members in locked position;

Fig. 2 is a similar view of the link with the two link members shown in disassembled position;

Fig. 3 is an edge view of the sectional link with the locking members in unlocked position; and

Fig. 4 is a sectional plan view of the sectional link on the line 4—4 of Fig. 1.

The sectional link in its general construction consists essentially of two C-shaped sections 10 and 11, alike in construction and having shanks 12 and 13 preferably made cylindrical in cross section. The ends of the shank 12 terminate in integral hooks 14 and 15 of approximately U shape, and the ends of the shank 13 terminate in similar integral hooks 16 and 17. The hooks 14, 15, 16 and 17 are approximately half round in cross section and the hooks 14 and 16 are adapted to overlie each other with their flat surfaces in contact, and the hooks 15 and 17 are adapted to similarly overlie each other with

the flat surfaces in contact, thus forming a link approximately cylindrical in cross section throughout its length.

The hooks 14 and 15 of the link section 10 are provided at their free ends with slots 20 and 21 adapted to be engaged by tongues 22, 23 projecting from the ends of the shank 13 and integral with the flat sides of the bases of the hooks 16 and 17 of the other link section 11. The free ends of the hooks 16 and 17 of the link section 11 are provided with slots 25, 26 adapted to be engaged by tongues 27, 28 formed integrally on the ends of the shank 12 of the other link section 10 and projecting onto and integral with the flat sides of the hooks 14 and 15 of the link section 10. The terminals of the hooks 14 and 15 are adapted to abut against the ends of the shank 13, and the terminals of the hooks 16 and 17 abut against the ends of the shank 12 at the time the link sections 10 and 11 are superimposed one upon the other, as indicated in Figs. 1, 3 and 4. By the arrangement described the link sections are held against movement, but the link sections can be lifted one off the other to open the link for engagement of the link with the parts to be connected with each other.

In order to lock the link sections 10 and 11 together after they are superimposed as above described, the following arrangement is made: On the shank 12 are mounted to turn two locking sleeves 30 and 31 provided with Z-shaped slots 32, 33 into which project pins 34, 35 integral with the shank 12. Similar locking sleeves 40 and 41 are mounted to turn on the shank 13, and the sleeves are provided with Z-shaped slots 42, 43 into which project pins 44, 45 formed integral on the shank 13. The sleeves 30, 31, 40, 41 are shown in unlocked position in Fig. 2, that is, the sleeves on the corresponding shank are close together with the tongues 22, 23 and 27, 28 completely exposed to allow of inter-engaging said tongues with the corresponding slots 20, 21 and 25, 26. When this has been done, the sleeves 30, 31 and 40, 41 are turned on their corresponding shanks 12 and 13 and move outwardly from each other to slip over the free ends of the corresponding hooks 16, 17 and 14, 15 and likewise over portions of the corresponding tongues 22, 23 and 27, 28 to securely lock the link sections 10 and 11 in closed position.

It is understood that the link sections 30, 31

31 and 40, 41 are held against accidental movement in their innermost unlocking positions or in their outermost locking positions by the corresponding pins 34, 35 and 5 44, 45 engaging the slots 32, 33, 42, 43, as will be readily understood by comparison of Figs. 1 and 2.

In order to relieve the tongues 22, 23, 27, 10 28 of some of the sidewise and endwise strain use is made of lugs 50, 51 on the flat sides of the hooks 14 and 15, and similar lugs 52, 53 on the flat sides of the hooks 16 and 17, the lugs 50, 51 engaging corresponding recesses 54, 55 formed on the flat sides of the 15 hooks 16 and 17 and the lugs 52, 53 engaging corresponding recesses 56, 57 formed on the flat sides of the hooks 14 and 15.

From the foregoing it will be seen that the sectional link is very simple in construction 20 and arranged to permit convenient and quick opening of the link sections 10 and 11 to engage the same with the parts to be coupled together. It will also be noticed that after the link sections are engaged 25 with the parts to be coupled and are superimposed they are quickly locked in position to prevent accidental opening of the link sections.

Although the sectional link is more especially designed for use on oil well drilling 30 tools have clevises and bails fixed or arranged permanently on the blocks or tools, it is evident that I do not limit myself to this particular use of the sectional link. 35 By providing the tongues 22, 23, 27 and 28, the link sections are not liable to be distorted or bent when the link is subjected to a heavy strain.

Having thus described my invention, I

claim as new and desire to secure by Letters Patent:—

1. A sectional link, comprising two link sections each having a shank and a hook at each shank end, the hooks of a link section and the shank of the other link section having interlocking engaging means, and locking members movable on the said shanks and engaging the corresponding inter-engaging means of the two link sections to lock the latter together. 45

2. A sectional link, comprising two link sections having halved overlying hook members, and a shank between the hook member of each link section, each shank having tongues, and the free ends of the hooks having slots, of which the slots of the hook members of one link section engage the tongues on the shank of the other link section, and locking means movable on the shanks and engaging the corresponding interlocked tongues and slots to hold the link sections locked together. 55

3. A sectional link, comprising two link sections each having a shank and a hook at each end of each shank, the shanks having integral tongues and the free ends of the hooks having slots of which the slots of the hooks on one link section engage the tongues on the shank of the other link section, locking sleeves mounted to turn and to 70 slide on the said shanks and adapted to fit over the corresponding interlocking tongues and slots, the sleeves having Z-shaped slots, and pins on the shanks engaging the said Z-shaped slots in the sleeves to hold the latter in locked or unlocked position. 75

JOHN M. THOMSON.
